UNITED STATES PATENT OFFICE.

HENRY M. RAMSAY, OF ALTOONA, AND JUSTUS A. RICKABAUGH, OF PITTSBURGH,
PENNSYLVANIA.

PAWL-AND-RATCHET MECHANISM.

1,207,076.

Specification of Letters Patent.

Patented Dec. 5, 1916.

Application filed July 5, 1916. Serial No. 107,495.

To all whom it may concern:

Be it known that we, HENRY M. RAMSAY and JUSTUS A. RICKABAUGH, both citizens of the United States, residing, respectively, at Altoona, in the county of Blair and State of Pennsylvania, and Pittsburgh, in the county of Allegheny and State of Pennsylvania, have invented certain new and useful Improvements in Pawl-and-Ratchet Mechanism, of which the following is a specification.

The invention relates to pawl and ratchet mechanism, and more particularly to the pawl construction which is shown as applied to use in connection with a hand brake on a car. The invention has for its principal objects: the provision of an improved self acting pawl, simple in construction and positive in action; and the provision of a pawl in which no additional parts are required by the self acting feature, which is substantially as cheap as the ordinary non-automatic pawl and which will wear indefinitely without getting out of order. One embodiment of the invention is illustrated in the accompanying drawings, wherein—

Figure 1 is a plan view of the mechanism; Fig. 2 is a side elevation; Fig. 3 is a plan view of the portion of the device upon which the pawl rests with the pawl removed; and Fig. 4 is a section through the pawl taken alone on the line IV—IV of Fig. 1.

The ratchet wheel 1 and the pawl 2 are preferably carried on a single metal base plate 3 which plate is held in position on the car member or other support 4 (Fig. 2) by means of the bolts 5 and 6.

The ratchet wheel 1 is mounted for rotation on the upstanding lug 7 of the base plate and may be of any approved form, the invention residing particularly in the pawl regardless of the kind of ratchet wheel with which it is used. The usual guard 8 is employed also integral with the base plate 3, and the ratchet wheel is rotated by the shaft 9 secured in the hub of the ratchet wheel in any desired way.

The left hand end of the base plate is provided with an integral upstanding sleeve 10 upon which the pawl 2 is pivoted, and resting upon the upper end of this sleeve is the washer 11 held in position against the end of the sleeve by means of the nut 12 threaded onto the end of the bolt 6. As

indicated in Fig. 2, the washer 11 is spaced above the top of the pawl so that the pawl may slide upward for the purpose herein-after set forth, and as required by the method of operation.

Surrounding the sleeve 10 and projecting upward from the base plate 3 are a pair of cam surfaces marked 13 and 14 on Fig. 3, the arrows on Fig. 3 indicating the direction in which the surfaces incline upward. The upper ends of these inclined surfaces terminate in flat surfaces 15 and 16 which rest against the under side of the pawl. The character of these surfaces will be understood by reference to Fig. 2, in which the surfaces 14 and 15 are shown in side elevation. The under surface of the pawl 2 is provided with a pair of downwardly projecting lugs 17 (Fig. 2) having their lower edges inclined so as to fit the inclined surfaces 13 and 14.

From the foregoing it will be seen that as the pawl is rotated in a counter-clockwise direction (Fig. 1) to release it from the ratchet teeth, it will be cammed vertically until its upper face engages the washer 11. If now the pawl is released, it will return to its original position, as indicated in Fig. 1, the inclined surfaces on the lugs 17 sliding downward and in a clockwise direction upon the inclined cam surfaces 13 and 14, such movement being due to gravity.

As a pawl of this type is relatively heavy, and the inclination of the cam surfaces is quite steep, a positive movement of the pawl to operative position is secured, so that the operator is relieved of the necessity of holding the pawl in operative position while he is turning the brake shaft 9 and applying the brake.

It will be seen that the construction herein set forth is relatively cheap and simple and that aside from the cam members which are made integral with the base plate, no addition or separate parts are required to make the device automatic as compared with the non-automatic pawl commonly employed in connection with brakes. The pawl itself supplies the necessary operating weight, so that no additional weight is required, and the mechanism requires no more attention or repair than the ordinary non-automatic pawl. The construction is applicable to the standard type of ratchet wheel now in use and comparatively slight changes only are

required in the pawl and base plate as compared with standard constructions, so that the device can be readily substituted for the non-automatic constructions now in use.

5 Other advantages incident to the cheapness and simplicity of the device will be readily apparent to those skilled in the art.

It will be understood that our invention 10 contemplates modifications and changes as well as a mere reversal of parts and that the principle involved is the same whether a pawl is caused to move rotarily to operating position by weight applied to an inclined surface or some other member is so operated.

15 What we claim is:

1. The combination with a substantially horizontal ratchet wheel, of a pawl working around a substantially vertical axis and having a limited amount of play in a vertical direction, a support for the pawl, and 20 coacting cam surfaces on the underside of the pawl and the support on which it turns arranged so that the weight of the pawl tends to cause it to rotate about its axis and give engagement between its end and the teeth of the ratchet wheel.

2. The combination with a ratchet wheel, 30 of a pawl mounted for rotation about an upright axis and for movement longitudinally of such axis, a support on which the pawl turns, and coacting inclined surfaces on the underside of the pawl and on the said support arranged to cam the pawl in a vertical direction when it is rotated to disengaged position, and to cause the pawl to 35 rotate automatically in the reverse direction when it is released from such position.

3. The combination with a ratchet wheel, 40 of a pawl mounted for rotation about an upright axis and for movement longitudi-

nally of such axis, a support on which the pawl turns, and coacting surfaces on the underside of the pawl and the said support and having such a relative inclination that 45 the pawl is caused to move in a vertical direction, when it is rotated to disengaged position.

4. In combination, a ratchet wheel member and a pawl member, one of which works 50 about a substantially vertical axis and has a limited amount of movement in a vertical direction, and coacting cam surfaces on the underside of such last member and the support on which it turns, arranged so that the 55 weight of such last member causes it to rotate about its axis and give engagement between the two members.

5. In combination, an operating member mounted for rotation about an upright axis 60 and having an end which swings toward and from operating position, a support on which the member turns, and coacting inclined surfaces on the underside of the member and on said support arranged to cam the 65 member in a vertical direction when it is rotated to inoperative position, and to cause the member to rotate automatically in the reverse direction when released.

6. The combination with a ratchet wheel, 70 of a pawl mounted for rotation about a vertical axis and having an upper and a lower face, a cam surface on one of said faces of the pawl, and another part having a cam surface opposing the cam surface of the 75 pawl, the parts being so arranged that when the pawl is in inoperative position pressure is exerted between the cam surfaces tending to rotate the pawl to operative position.

HENRY M. RAMSAY.

JUSTUS A. RICKABAUGH.
